Primary Examiner — Darlington Ly*(74) Attorney, Agent, or Firm* — McAndrews, Held & Malloy, Ltd.(57) **CLAIM**

The ornamental design for packaging, as shown and described.

DESCRIPTION

FIG. 1 is a front perspective view of packaging showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The stippled areas represent areas of contrasting appearance to the adjacent non-stippled areas.

The dotted lines shown in FIGS. 1 and 4 represent perforations and form no part of the claimed design.

The vertical and horizontal shade lines in the figures are used to show that the surfaces are substantially planar and not to be interpreted as surface ornamentation.

The even-length dashed broken line rectangles in FIGS. 1 to 6 illustrate portions of the packaging that form no part of the claimed design.

1 Claim, 4 Drawing Sheets

Matter enclosed in heavy brackets [ ] appears in the original patent but forms no part of this reissue; matter printed in italics indicates the additions made by reissue.
